UNITED STATES PATENT OFFICE.

DANIEL A. DORAN, OF YONKERS, NEW YORK, ASSIGNOR TO MARY I. DORAN, OF YONKERS, NEW YORK.

MAIL-BOX AND OTHER DEVICE.

1,349,413.

Specification of Letters Patent. Patented Aug. 10, 1920.

Application filed September 29, 1919. Serial No. 327,169.

To all whom it may concern:

Be it known that I, DANIEL A. DORAN, a citizen of the United States, and residing at Yonkers, in the county of Westchester and 5 State of New York, have invented certain new and useful Improvements in Mail-Boxes and other Devices, of which the following is a specification, such as will enable those skilled in the art to which it appertains to 10 make and use the same.

This invention relates to mail boxes and particularly to devices of this class used in apartment houses, and the object of the invention is to provide a mail box which is 15 adapted to be automatically raised and lowered in a suitable shaft whereby a party or tenant may receive mail from the ground floor of the building and automatically raise such mail to a predetermined point on the 20 floor of the building in which the apartment of such tenant is located; a further object being to provide means automatically actuated by the opening of a door to the shaft in which the mail-box operates for raising 25 the mail-box into juxtaposition with the door opening of said door and also to provide means whereby the closing of said door will automatically lower the mail-box in said shaft; a still further object being to provide 30 a structure of the class specified which may also be used as, or in dumbwaiter apparatus and other, or similar carriers; and with these and other objects in view the invention consists in a device of the class and for the 35 purpose specified, constructed and operating as hereinafter described and claimed.

The invention is fully disclosed in the following specification, of which the accompanying drawing forms a part, in which the 40 separate parts of my improvement are designated by suitable reference characters in each of the views, and in which:-

Figure 1 is a longitudinal sectional view through a mail-box shaft in the wall of a 45 building showing my improvement therein and indicating the method of its use, part of the construction being broken away and omitted;

Fig. 2 a partial section on the line 2—2 of 50 Fig. 1;

Fig. 3 a partial section on the line 3—3 of Fig. 2; and,

Fig. 4 a partial section on the line 4—4 of Fig. 2.

In Figs. 1 to 3 inclusive, I have indicated 55 at 5 part of a wall of a building in which is formed a vertical mail-box shaft 6, the top of which communicates with an enlarged compartment 7. Mounted on the opposite side walls of the shaft 6 are tracks 8 which 60 serve to guide a mail-box 9 in its vertical movement in said shaft. The opposite sides of said mail-box are provided with channels 10 which operate in connection with the tracks 8, as clearly shown.

The mail-box 9 is approximately rectangular in form and open at the top and provided with a bail or handle portion 11. An electric motor 12 is mounted within the compartment 7 at the top of the shaft 6 and provided with 70 a protruding shaft 13 on the outer end portion of which is mounted a spool 14 and a rope or cable 15 is wound on said spool and the free end of which is connected with the bail 11 as shown at 16. Mounted on said shaft inwardly of the spool 14 is a ratchet wheel 17 in connection with which a pawl 18 pivoted to a suitable bracket 19 is adapted to operate. The pawl 18 is normally held in engagement with the ratchet 17 by a spring 80 20 and the free end of the pawl 18 is L-shaped in form and provided with an arm 21, the free end portion of which is beveled as shown at 22 in Fig. 3 of the drawing.

A circuit make and break arm 23 is piv- 85 otally mounted within the shaft 6, or on one wall thereof as shown at 24 and is adapted to make and break the circuit through wires 25 and 26 of the motor 12, the wire 25 being connected with the pivoted end of the arm 23, 90 while the wire 26 connects with a contact device 27 supported on an arm 28 secured to a wall of the shaft 6.

At the top of the shaft 6 and in one wall thereof is a door opening 29 preferably located slightly below the compartment 7, and a hinged door 30 is adapted to close said door opening. The hinged side of the door 30 is provided on its inner face with an inwardly directed cam arm 31, the free end portion of which is beveled as shown at 32. The beveled portion 32 of the arm 31 is adapted to operate in connection with the make and break arm 23 to raise said arm and break the circuit through the wires 25 and 26 in the operation of closing the door and the cam arm 31 is also adapted to operate in connection with the arm 21 of the pawl 18 to

move said pawl out of operative connection with the ratchet 17 in the operation of closing the door. The shaft 6 or one wall thereof is provided adjacent to the lower end thereof 5 with an elongated slot or aperture 33 through which mail may be passed into the shaft 6, or the mail-box 9 in said shaft when said mail-box is in its lowest position as indicated in dotted lines in Fig. 1 of the drawing.

10 A shutter device 34 is mounted in the bottom portion of the shaft 6, said shutter consisting of a bottom 35 having raised side walls 36 one of which is adapted to register with the elongated slot or aperture 33 to 15 close the same and prevent the passage of mail into the shaft 6, when the mail-box 9 is in its raised position as indicated in full lines in Fig. 1. The shutter device 34 is normally held in its raised position by a 20 spring 37 mounted in the bottom of the shaft 6 and which operates in connection with the bottom 35 of the shutter device 34. When the mail-box 9 drops into its lowest 25 position by gravity, said mail-box moves the shutter device 34 downwardly into the position indicated in dotted lines in Fig. 1 and permits the passage of mail through the slot or aperture 33 into the mail-box 9.

The operation of my improved mail-box 30 device will be readily understood from the foregoing description when taken in connection with the accompanying drawing and the following statement. It will be understood that the mail-box 9 is normally in 35 its lowest position in the shaft 6, or in the position indicated in dotted lines in Fig. 1, and the door 30 is normally closed. When the door is in its closed position it will be seen that the make and break arm 23 is in 40 its raised position, or out of contact with the contact device 27 and the pawl 18 is held out of engagement with the ratchet 17 by the cam arm 31. In this position of the parts a letter-carrier may pass mail through the 45 slot or aperture 33 into the box 9 and when the tenant desires to raise the mail-box 9, the door 30 is opened by hand which operation releases the cam arm 31 from the arm 21 of the pawl 18 and permits the make and 50 break arm 23 to move into contact with the contact device 27 thus completing the circuit through the wires 25 and 26 and the motor 12 is then automatically put in operation. The operation of the motor 12 will rotate the shaft 13 and the spool 14 thereon to 55 wind the rope or cable 15 on said spool thus raising the mail-box in the shaft 6, in which operation the rope or cable 15 passes through a slot 38 in the make and break arm 23. When the mail box 9 reaches the desired 60 position adjacent to the door opening 29 a knot 39 or other enlargement on the rope or cable 15 operates in connection with the make and break arm 23 to raise the same and break the circuit through the wires 25 and 65

26 thus automatically stopping the motor 12. In the last named or raised position of the mail-box 9, the pawl 18 operating in connection with the ratchet 17 will hold said mail-box in its raised position or will 70 prevent the rotation of the motor shaft 13, and after the mail has been removed from the box 9 by the tenant, the operation of closing the door 30 will depress the arm 21 of the pawl 18 to disengage said pawl from the ratchet 17 and permit the rotation of the shaft 13 and the mail-box 9 will then drop by gravity in the shaft 6 until it reaches the position indicated in dotted lines in Fig. 1, and in this operation the spring 30 37 will be compressed and the shutter device 34 moved downwardly as hereinbefore stated.

In order that the device may be fool-proof and positive in action, I provide a spring 40 85 which will normally hold the door 30 in a closed position so that when the tenant has removed the mail from the box 9 and the door 30 is released, it will automatically move into its closed position to release the 90 pawl 18 from the ratchet 17 and permit the mail-box 9 to drop into its lowest position.

It will be understood that while I have shown certain details of construction for carrying my invention into effect and have 95 illustrated but one shaft and mail-box therein, my invention is not necessarily limited to these details, nor am I limited to the specific use of the apparatus herein shown and described for the raising and lowering 100 of mail matter, as said apparatus may be used as, or in a dumbwaiter, or similar carrier, and various changes in and modifications of the details of construction herein shown and described may be made, within 105 the scope of the appended claims, without departing from the spirit of my invention or sacrificing its advantages.

Having fully described my invention, what I claim as new and desire to secure by Letters Patent, is:-

1. In a device of the class described, a shaft at the top portion of which is a door opening and at the bottom portion of which is an elongated aperture, a door adapted to 115 close said door opening, a mail-box movable vertically in said shaft, said mail-box being normally in its lowest position, and means whereby the opening of said door will automatically cause said mail-box to be raised 120 in said shaft.

2. In a device of the class described, a shaft at the top portion of which is a door opening and at the bottom portion of which is an elongated aperture, a door adapted to 125 close said door opening, a mail-box movable vertically in said shaft, said mail-box being normally in its lowest position, means whereby the opening of said door will automatically cause said mail-box to be raised in said 130

shaft, and means for automatically stopping the upward movement of the mail-box in said shaft.

3. In a device of the class described, a shaft at the top portion of which is a door opening and at the bottom portion of which is an elongated aperture, a door adapted to close said door opening, a mail-box movable vertically in said shaft, said mail-box being normally in its lowest position, means whereby the opening of said door will automatically cause said mail-box to be raised in said shaft, means for automatically stopping the upward movement of the mail-box in said shaft, and means for holding the mail-box in its raised position.

4. In a device of the class described, a shaft at the top portion of which is a door opening and at the bottom portion of which is an elongated aperture, a door adapted to close said door opening, a mail-box movable vertically in said shaft, said mail-box being normally in its lowest position, means whereby the opening of said door will automatically cause said mail-box to be raised in said shaft, means for automatically stopping the upward movement of the mail-box in said shaft, means for holding the mail-box in its raised position, and said first named means operating to automatically release said last named means to permit of the downward movement of said mail-box in said shaft in the operation of closing the door.

5. In a device of the class described, a shaft at the top portion of which is a door opening and at the bottom portion of which is an elongated aperture, a door adapted to close said door opening, a mail-box movable vertically in said shaft, said mail-box being normally in its lowest position, means whereby the opening of said door will automatically cause said mail-box to be raised in said shaft, means for automatically stopping the upward movement of the mail-box in said shaft, means for holding the mail-box in its raised position, said first named means operating to automatically release said last named means to permit of the downward movement of said mail-box in said shaft in the operation of closing the door, and a spring actuated shutter device in the bottom portion of said shaft and adapted to automatically close said elongated aperture when the mail-box is in its raised position.

6. In a device of the class described, a shaft at the top portion of which is a door opening and at the bottom portion of which is an elongated aperture, a door adapted to close said door opening, a mail-box movable vertically in said shaft, said mail-box being normally in its lowest position, means involving an electric motor for raising said

mail box in said shaft, and means on said door and in the top portion of said shaft for automatically putting said motor in operation to raise said mail-box in the operation of opening said door.

7. In a device of the class described, a shaft at the top portion of which is a door opening and at the bottom portion of which is an elongated aperture, a door adapted to close said door opening, a mail-box movable vertically in said shaft, said mail-box being normally in its lowest position, means involving an electric motor for raising said mail box in said shaft, means on said door and in the top portion of said shaft for automatically putting said motor in operation to raise said mail-box in the operation of opening said door, means for automatically breaking the circuit to said motor for stopping the upward movement of said mail-box in said shaft, and means for holding said mail-box in its raised position.

8. In a device of the class described, a shaft at the top portion of which is a door opening and at the bottom of which is an elongated aperture, a door adapted to close said door opening, a mail-box movable vertically in said shaft, said mail-box being normally in its lowest position, means involving an electric motor for raising said mail-box in said shaft, a make and break arm mounted in the top portion of said shaft and adapted to open and close the circuit to said motor, and means on said door adapted to operate in connection with said make and break arm to normally hold said arm in its inoperative position when the door is closed whereby the opening of said door will automatically close the circuit to said motor and raise the mail-box in said shaft.

9. A device of the class described comprising a suitable shaft having a door opening, a door adapted to close said opening, a mail box movable in said shaft, said mail box being normally in its lowered position, and means actuated by the opening of said door for automatically moving said mail box into a raised position.

10. A device of the class described comprising a suitable shaft having a door opening, a door adapted to close said opening, a mail box movable vertically in said shaft, said mail box being normally in its lowered position, means actuated by the opening of said door for automatically moving said mail box into a raised position, and means for automatically stopping the upward movement of said mail box and for holding it in a raised position.

In testimony that I claim the foregoing as my invention I have signed my name this 18 day of September, 1919.

DANIEL A. DORAN.
